HEAT EXCHANGER.

Application filed October 30, 1924. Serial No. 746,736.

The present invention aims to provide a heat exchanger adapted for various uses, a modification and certain clearly indicated parts of which are shown in my application 5 Serial No. 665,266, filed September 28, 1923. Several alternative improvements of the invention are illustrated in the accompanying drawings in which Fig. 1 is a vertical longitudinal section of a portion of a heat exchanger. 10 Fig. 2 is a vertical section through a modified form of heat exchanger. Fig. 3 is a fragmentary front view showing the staggered arrangement of heat exchanging elements of Figs. 1 and 2. Fig. 4 is a vertical section of the heat exchanger similar to that shown in Fig. 2, but showing certain of the heat exchanging elements inclined and others disposed horizontally. 20 Figs. 5 and 6 illustrate a combined heat exchanger and dust catcher, Fig. 6 being a section on line 6—6 of Fig. 5. Fig. 7 illustrates in horizontal section a form of heat exchanger adapted to absorb 25 heat from various hot liquids issuing from industrial apparatus and for transferring said heat to another fluid.

Fig. 8 illustrates a heat exchanger similar 30 to Fig. 7, but adapted to absorb heat from hot fluids coming from two separate sources;

Fig. 9 shows an apparatus adapted to absorb heat of waste gases coming from a boiler or the like and adapted to transfer the heat 35 to another medium such as a body of water;

Fig. 10 illustrates diagrammatically a further modification of heat exchanger adapted 40 to transfer the heat of waste gases issuing from a boiler to two other mediums one of which is gaseous and the other of which is liquid;

Figs. 11 and 12 illustrate alternative constructions.

Referring in detail first to Fig. 1 of the 45 drawings 10 is a duct through which hot gases are passed, for example, from the inlet end 12 toward the outlet end 14. Extending transversely across this duct are a plurality of heat exchanging elements designated as a whole by 50 numeral 16. Each of these elements comprises a hollow tubular member containing a fluid 18 in the bottom thereof and a vapor of such fluid in the remaining space 20. The elements 16 are preferably hermetically sealed and practically all of the air is exhausted therefrom. Extending longitudinally through the space 20 of each heat exchanging element is a pipe or conduit 22. As thus arranged it is evident that by circulating a fluid through the several pipes 22 a transfer 55 of heat can be obtained. The hot gases flowing through the duct 10 contact with the multiplicity of tubular heat exchanger units 16, the latter containing a liquid which is evaporated. 60 In Fig. 1 the relatively cool fluid to be heated is fed from a header 24 and circulated through the several pipes 22 which extend longitudinally through the heat exchanger elements 16. Fluid thus heated passes out as 65 indicated by the arrow to an outlet header 26, the several pipes 22 being connected by bends 28 at the ends of the exchanger elements 16. The exchanger elements are arranged in banks and the banks are staggered as illustrated in Fig. 3. 70 In Fig. 2 I have shown a duct 30 in which the hot gases are circulated in the direction of the arrows from the inlet end 32 to the outlet end 34. This duct is provided with a vertical wall or partition 36 which with the wall 38 at the left forms another duct 40 through which a fluid is circulated as indicated by the arrows. In this figure I also show a supply header 42 to which is connected a series of 75 pipes 44 which project into the heat exchanger units 16 which in this case are inclined. The pipes 44 extend only a short distance into one end of each unit 16 and are formed with return bends 46 at their inner ends so that the 80 cool fluid to be heated can flow serially through the several pipes 44 and outward to the header 46. The upper most unit 16 in Fig. 2 contains the greatest volume of liquid 85 18 and the lowest unit contains the least amount, the intermediate units being substantially uniformly graded between these two extremes. It is apparent that the amount of absorption for the different parts of the exchanger may vary and that by using a greater or less amount of liquid 18 in different parts of the exchanger this variation may be compensated for and thus prevent bursting of the units in the hottest zone. 90 The hot gas or other fluid to be cooled 95 passes through the duct 30 progressively giving up its heat to the successive exchanger elements 16 and evaporating the liquid con-

tained therein. The fluid to be heated which is circulated through the pipes 44 progressively condenses the vapor in the said exchanger elements 16, thus absorbing the heat therefrom. There will be a different pressure and temperature inside of each horizontal row of heat exchanger elements. There is therefore a perfect counterflow action. It is apparent that in the embodiment of the invention shown in Fig. 2 there is a heat transfer from the gases circulated through the duct 30, to a fluid such as gas or air circulated through the duct 40 and also a transfer of heat to a fluid which may be a liquid circulated through the pipes 44 from the header 42. I have discovered that with such an apparatus and method of operating the heat transfer is of much higher order than that obtained in the usual form of direct type air heaters in which the gases and air pass either in parallel or countercurrent through separate passages. I have also determined that when water or other fluid is circulated through the pipes 44 which are in contact with a vapor the heat transfer is much more rapid than that obtained in forms of exchanges heretofore used.

In Fig. 4 I have illustrated in vertical section a heat exchanger combining in one structure the arrangements shown in Figs. 1 and 2. In this figure the upper heat exchanger units 16^a are disposed horizontally like those shown in Fig. 1 and the pipes 22 extend horizontally through the vapor space of such elements. The lower section of this heat exchanger is made up of elements 16^b which are inclined to the horizontal and provided with return bend pipe sections 44^a substantially the same as those shown in Fig. 2. As before, the hot gases circulate upward in the direction of the arrows through a duct 30^a and the air or other fluid to be heated circulates downwardly through a duct 40^a.

In Figs. 5 and 6 I have illustrated a heat exchanger well adapted to absorb the heat from the waste gases coming from a boiler or like piece of industrial apparatus and adapted to transfer the heat thereof to two other mediums, one being a gaseous fluid such as air and the other being a liquid such as water. This apparatus is particularly well adapted for use as a combined air heater and economizer and is also provided with means for trapping the solid material such as flue dust and carbon particles entrained in the waste gases. In this form of the apparatus the heat exchanger elements 16^c are disposed vertically and filled with a suitable fluid 18 as before with a space 20^a at the top which is filled with a vapor of the liquid 18. The hot waste gases from the steam boiler or other apparatus flow in the direction of the arrows from the inlet end 48 toward the outlet end 50 of a duct 52. A partition wall 54 separates the duct 52 from a second duct 56

through which air or other fluid is adapted to be circulated in the direction of the arrows so as to absorb the heat from the upper portion of the units 16^c. Certain of the units 16^c terminate as indicated at 58 just below transversely extending pipes 60 which connect headers 62 and 64. Similar units, two of which are shown in dotted lines staggered with relation to the units shown in full lines in Fig. 5, extend upwardly to the top surface 62 of the apparatus, so that the heat thereof can be in part transferred to the feed water or other fluid circulated from the headers 62 and 64 through the pipes 60. The space surrounding the pipes 60 and upper portions of the units 16^c will be packed with a suitable heat conducting material as indicated at 66. A dust catcher 68 comprising a substantial rectangular tank is disposed below the units 16^c and is adapted to trap dust particles entrained in the gases flowing through the duct 52. This dust catcher is provided with a plurality of partition walls 70 dividing the same into a plurality of compartments, each compartment communicating by means of a branch 72 with a pipe 74 through which the dust may be sucked out by vacuum or washed by a stream of water circulating through the pipe.

In Fig. 7 I have illustrated an apparatus adapted to absorb heat in the liquid coming from various types of industrial apparatus and for transferring such heat to another fluid such as water. In this form of device hot liquid such as oil coming from an industrial apparatus through a pipe 76 will flow through a conduit 78, giving up its heat by vaporizing a liquid in the heat exchanger elements 16^d. The cooled oil or other liquid will be carried off by a suitable outlet pipe or header 80. The water or other fluid to be heated will be supplied from a main 82 and flow through the conduit 84 in contact with the upper ends of the heat exchanger elements 16^d and the heated water or other liquid will flow in the direction of the arrow to the outlet main 86.

Fig. 8 exemplifies a heat exchanger adapted to absorb the heat from two hot fluids coming from an industrial apparatus and for transferring such heat to another fluid. In this apparatus hot air passes through a duct 88 in the direction of the arrows and gives up its heat to the liquid contained in the exchanger elements 16^e. Hot oil passes from a main header 90 through a conduit 92, also giving up its heat to the liquid within the unit 16^e, the oil thus cooled, passing out by way of a pipe 94. This particular type of apparatus adequately meets the cooling needs of a large steam turbo electric generating apparatus. With such apparatus it is highly desirable to cool the oil and air and to recirculate them. It is advantageous in many localities to use salt water as a cooling me-

dium. In such cases the different parts of the apparatus with which the salt water contacts will be protected by a suitable coating to avoid corrosion. The water will be supplied through a main 96 and passed through a conduit 98 in contact with the upper portion of the exchanger units 16^e and will be discharged through an outlet main 100.

Fig. 9 illustrates a heat exchanger adapted to absorb heat from waste gases coming from a boiler or the like, and for transferring the heat to another medium such as water. In this case the hot gas issuing from the boiler passes through the duct 102, giving up its heat to the liquid in the exchanger units 16^f which in turn transfer the heat to water or other fluid circulating through a conduit 104 from an inlet main 106 to the outlet main 108.

Fig. 10 illustrates an apparatus adapted to absorb heat from the waste gases emanating from a boiler or the like and for transferring such heat to two other mediums one of which is a gaseous fluid such as air and the other of which is a liquid. This particular embodiment of the invention is adapted to serve as a combined air heater, economizer and dust catcher. In this figure 110 represents a conventional type of water tube boiler having an outlet port 112 for the hot waste gases, the latter starting their journey toward the stack through a duct 114 disposed horizontally over the tube banks of the boiler. Projecting into the duct 114 are a series of heat exchanger elements 16^g which, like those previously described, contain liquid in their lower parts and a vapor in their upper parts. Part of the heat of the waste gases is transferred through the units 16^g to a current of air flowing through a duct 116 and the remainder of the heat is transferred to water or other liquid which enters a pipe 118 and passes through a duct 120 into which the upper ends of the heat exchanger elements 16^g project as shown in dotted lines, the heated water passing out by way of pipe 122.

This apparatus is also provided with a catch hopper 124 having an upper portion 126 slightly elevated above the lower wall of the duct 114 so that a portion of the dust entrained in the waste gases flowing through said duct 114 will be trapped and flow into the hopper 124. Beyond the hopper 124 is located a second hopper 128 of relatively greater capacity. This connects with the duct 114 by means of a vertical duct 130 of gradually decreasing sectional area so that the velocity of the fluid stream passing therethrough is substantially increased. That portion of the dust entrapped by the hopper 124 will be discharged downwardly into the bottom of the hopper 128 and the dust-free waste gas will escape to the stack through a pipe 132. At the point of connection between the hopper 128 and the hopper 124, I provide a pivoted valve or damper 134.

The hot gases in their passage through the duct 114 of necessity strike the heat exchanger elements 16^g and the dust particles entrained in such gases impinge on these elements and fall on the comparatively smooth plate 136 which forms the lower portion of the duct 114. The greater proportion of the dust thus precipitated is trapped in the hopper 124 and is gradually discharged past the damper 134 to the hopper 128 and the remainder of the dust particles are trapped in the hopper 128 after their passage through the duct 130.

In the various embodiments of the invention herein illustrated the ducts or passages may be constructed of steel plate or other suitable material properly reinforced, fitted and fabricated, and will of course be covered where necessary with suitable heat insulating material not shown in detail on the drawings. The heat exchanger elements may be disposed either horizontally or vertically or at different angles according to the design of the particular piece of apparatus in which they are used and other conditions encountered in the design.

While I prefer to make the heat exchanger elements of round metal tubes and to partially fill them with water and exhaust the air from the remaining portion so that it will contain substantially only water vapor, and then hermetically seal said elements by welding or otherwise, it is to be understood that I may construct these elements of any suitable material of any desired shape, the important point being that I partially fill such elements with any desired liquid or mixture of liquids and keep them substantially free from air in any desired manner.

The invention may be utilized in industrial applications other than those specifically referred to hereinbefore, for example, the heat exchanger elements may be incorporated in apparatus for abstracting a sensible heat and obnoxious fumes from waste gases coming from a smelter or similar industrial apparatus. Such gases frequently contain fumes which are both dangerous and obnoxious and form a nuisance to the surrounding neighborhood when discharged into the atmosphere. The apparatus herein described provides the easiest, most feasible and most economic method for preventing such obnoxious fumes from being discharged into the atmosphere. The apparatus disclosed being adapted to cool such fumes to a point where sublimation occurs, that is to say such gases change almost instantly from a gaseous to a solid state without becoming a liquid, and in most cases they sublime into a fine powder or dust.

In Fig. 12 I have illustrated a slightly modified form of heat exchangers unit in which the tops of the heat exchanger elements 16^h are joined to pipes 16^a which carry a cool medium to be heated, the lower por-

tions of said pipes being exposed to the vapor in said elements. The joining of the elements to the pipes may be accomplished by welding, or in any desired way. The units 5 thus formed will be economical to manufacture, convenient for shipment, easy to erect, and will permit a close nesting of the elements.

In Fig. 11 I have illustrated a slightly 10 modified form of heat exchanger unit in the form of a U-tube having vertical legs 16^h and 16^j joined by a bridge portion 16^k. The lower portion of the legs 16^h and 16^j are filled with a suitable liquid adapted to absorb the 15 heat passed through the duct into which the lower part of the U-tube projects. The upper legs 16^h and 16^j contain a vapor which is adapted to be condensed by the fluid passed through the upper conduit. The U-tubes 20 may be either arranged in the conduits in the manner illustrated or they may be turned 90° so as to permit of closer nesting. This type of exchanger unit is somewhat less expensive 25 to manufacture it being apparent that because of the U-connection at the bottom, the closures corresponding to the closures in the lower ends of the single tubes is done away with. In other words, with the U-tube type 30 there are two closures necessary at the top of the legs 16^h and 16^j. On the other hand for a given capacity using simple straight 35 tubes we would require two straight tubes each of which would have to be closed at the top and bottom, that is four closures for the simple straight tubes against two closures for the U-tube type.

In experiments which I have made heat 40 exchangers of the type herein described with tubes of steel and with tubes of brass, I have secured a much higher heat transfer in British thermal units per degree difference in 45 temperature per hour from the hot surface of the tubes to the air, and also from the vapor to the water in the pipes exposed thereto, than has been obtained in the air heaters and 50 economizers now generally in service. The data obtained indicate that the more nearly complete the air exhaustion, the better the heat transfer. They also indicate that the 55 pressure in the tubes will not rise to an amount that will distort them past the elastic limit, or burst them, with the hot fluid entering the heat exchanger at 900° F. These experiments also show that there is an extremely fast, rapid, efficient and continuous circulation existing in each element when the heat exchanger is in service.

There are many advantages of my indirect 60 type of heat exchanger as compared with the usual direct type of heat exchangers now in use in industrial and generating plants. In most of the power stations now in operation the gases are leaving the boilers at a fairly high temperature, many of them up as high as 65 600° F. and some even higher. Some power

stations are equipped with economizers, some with air heaters, and a few with both economizers and air heaters arranged in series. With an economizer it is possible to save a large 70 percentage of the waste heat in the gases if we feed the economizer with low temperature water, such as water at or somewhat near the hotwell temperature from a condenser. By this means we make an efficient recovery from 75 our waste gases, but we sacrifice to a great extent, the economy that can be derived by bleeding the steam turbines. A well designed air heater can extract a fairly large percentage of the heat in the waste gases coming 80 from the boiler, but inasmuch as the mass flow of the gas is always substantially greater than the mass flow of the air needed for combustion, the air heater alone is inherently inefficient. The combination of an 85 economizer and an air heater in series is more efficient, but such an arrangement is costly and requires a large amount of space. A very efficient apparatus for extracting the 90 heat from the gases coming from a boiler is the novel arrangement shown in Figs. 2 and 95 5. In this apparatus there is a progressive serial heat transfer from the hot medium to be cooled, namely, the waste gases from a boiler to the cool mediums to be heated, namely, the air for combustion and the feed water 100 for the boiler. The heat transfer takes place in one small compact apparatus, each of my heat exchanger tubes extracting heat from the gases and transferring part of it to the air and part to the water. My apparatus is 105 flexible in design. For instance, the area exposed to the hot gases may be proportioned for any desired heat drop. The areas receiving the condensed vapor for transmitting the 110 heat to the air and water may be definitely proportioned so that this heat will properly be divided. In the usual forms of direct type air heaters the gases and air pass through a plurality of small channels, sometimes parallel, sometimes perpendicular to 115 one another. Most of the air heaters in present practice are constructed of thin metal. It is a well known fact that the transfer of heat from one gas to another in such prior apparatus is of a low order. In the usual 120 form of direct transfer economizer the gas passes over a number of tubes in which the water to be heated flows. While the transfer rate in this case is somewhat higher than in the air heater, it is still of a comparatively low order.

In my apparatus the hot gases are in contact with tubes containing a liquid which is evaporating and I have discovered that the 125 heat transfer in this case is of a much higher order than in either of the first mentioned cases. The air to be heated is in contact with tubes containing condensing liquid, and this transfer is also of a much higher order than that of the ordinary air heater. The water 130

- to be heated is in contact with a surface or surfaces receiving heat from a condensing vapor and the heat transfer in this particular case is many times that obtained in the 5 usual type of direct economizer, in fact, it is nearer to the very high rate of heat transfer obtained in a condenser. For instance, in the ordinary direct economizer the rate of heat transfer into the water would probably 10 be of the order of about 5 B. t. u. per square foot per degree difference per hour. In a condenser this rate of transfer is of the order of 400 to 800 B. t. u. per square foot per degree difference per hour.
- 15 For example, my heat exchanger shown in Fig. 10 above and receiving the waste gas from a cross drum water tube boiler, the gases would leave such a boiler under normal operating conditions at, say, 550° F., leaving 20 the heat exchanger at any desired temperature. The air heating surface would be proportioned so as to receive any desired percentage of the heat absorbed in the lower portion of the heat elements and the water heating 25 surface proportioned to absorb the remainder. In an old power station where no provision has been made for bleeding the steam turbines, it would probably be advisable to pass all of the condensate through 30 the heat exchanger, entering same at a temperature at or near the hotwell temperature. In a new station it may be advisable to pass only a portion of this low temperature water through the heat exchanger, then to discharge 35 said water into the suction lines of the boiler feed pumps or into a closed heater forming an integral part of the usual water heating system utilizing steam bled from the turbines, such as are now installed in most modern 40 power stations. With such an arrangement I cut down the enormous waste of heat carried by gases into the atmosphere, and am still able to take advantage of the efficiencies gained by bleeding the steam turbines to a 45 point almost equal to the usual practice, thus giving us a substantial gain in economy over the present practice.
- In the usual type of air heater and economizer, if one of the elements comprising the 50 apparatus should break it is necessary to shut the apparatus down, as soon as possible repair and replace said element, as they are always connected together. In my apparatus each individual heat exchanger tube is a 55 separate and distinct element, and if a few should break there is no necessity of shutting the apparatus down, and the result would simply be a very small decrease in efficiency.
- 60 In many industrial enterprises where heat exchangers are used or where they may be used in future, the fluids or mediums to be cooled have corrosive effects and in such cases my heat exchanger is superior to the direct 65 forms now in use. For example, the waste gases leaving boilers and many other apparatuses deriving their heat from coal burning furnaces, contain sulphur dioxide and other gases together with water vapor. At a certain temperature which is usually less than 70 the exit temperature of the gases leaving a highly efficient heat exchanger, an acid is formed which deposits on the heat absorbing elements of the heat exchanger, corroding and finally destroying them. The same is also 75 true of some fluids used as a cooling medium. For instance, for industrial plants located near an ocean, salt water is one of the most easily obtainable and economical agents for use as a cooling fluid or medium. It is a well 80 known fact that salt water, especially when it is heated, has a severe corrosive effect upon many metals. In my indirect heat exchanger only a portion of the heat absorbing or heat releasing surfaces are exposed to the fluids 85 or mediums to be heated or cooled, and if only one of said mediums has a corrosive action, then said action is limited to the area exposed. Said area with my heat exchanger built of individual elements, having much 90 higher transfer rates than the usual elements now in use for direct heaters, will obviously be smaller and can be far more easily and economically protected by a non-corrosive coating or by using a non-corrosive material 95 for the particular part exposed to corrosive action. Considering a case where we are extracting the heat from a corrosive fluid, such as waste gas from coal fired boilers and at or near the rear end of our heat exchanger, we 100 desire to maintain an exit temperature of 150° F., and our fluids to be heated have an entering temperature of 70° F., it is a well known fact that with usual conditions of humidity and moisture in the coal, a corrosive liquid will be deposited upon the elements of any direct type of heat exchanger. The temperature of the heat absorbing surface will necessarily be an arithmetical means 105 between the above mentioned temperatures 110 irrespective of the areas of the heat absorbing and releasing surfaces. Inasmuch as the surfaces in my heat exchangers are separate and distinct by themselves, and my transfer is indirect instead of direct, it is possible 115 with my heat exchanger to maintain a temperature of the heat absorbing surfaces above the dew point of the waste gas leaving the exchanger.
- My heat exchanger elements are well 120 adapted for the application of any form of extended surface. If my heat exchangers are manufactured of round metallic tubes, the application of extended surface would of course decrease the amount of round tube 125 area necessary.
- My apparatus is well adapted for the application of any desired soot-blowing or washing arrangement to keep the elements 130 free from too great an amount of dirt and

dust. For instance, in using my heat exchanger as an air heater with waste gases from a boiler, a soot-blowing apparatus similar to that now used for water tube boilers 5 may be installed and the problem of cleaning the apparatus is satisfactorily taken care of. Such an apparatus or any method as efficient or as satisfactory could not be installed on the usual types of air heaters now in service, 10 and it is clear that my indirect heat exchanger has a distinct advantage in the matter of cleaning.

Though I have described with great particularity the specific construction of the various structures embodying the invention it 15 is not to be construed that I am limited thereto as various changes and substitution of mechanical equivalents may be made by those skilled in the art without departing from the 20 invention as defined in the appended claims.

What I claim is:—

1. A heat exchanger comprising a plurality of containers each carrying a liquid in its lower portion which is exposed to the hot 25 medium to be cooled and adapted to carry a vapor generated from said liquid in an upper portion which is exposed to the cool medium to be heated, and pipes arranged to carry the cool medium and in contact with said vapor 30 in the successive containers.

2. A heat exchanger comprising a number of containers, each carrying a liquid in its lower portion which is exposed to a hot fluid to be cooled, and adapted to carry a vapor 35 generated from said liquid in an upper portion, the tops of said containers being attached to pipes arranged to carry the cool medium, said vapor being in contact with a portion of the surface of said pipes.

40 3. A heat exchanger comprising in combination a duct for the passage of a hot gaseous medium, a second duct adjacent to the first for the passage of a gaseous medium to be heated, means for effecting an exchange of 45 heat comprising a plurality of evacuated containers partially filled with liquid to be vaporized having portions extending into the path of the gases in each duct, and means for transferring a portion of the heat to a 50 liquid comprising a third duct in contact with the containers to absorb heat from the vapor by conduction.

55 4. A heat exchanger comprising in combination a duct for the passage of a hot gaseous medium, a second duct adjacent to the first for the passage of a gaseous medium to be heated, means for effecting an exchange of 60 heat comprising a plurality of evacuated containers partially filled with liquid to be vaporized 65 extending into each duct in the paths of the two gases, and means for transferring a portion of the heat to a liquid in circulation comprising a third duct extending into the containers and exposed to the vapor 70 therein.

5. A heat exchanger comprising in combination a duct for the passage of a hot fluid medium, a second duct adjacent and parallel to the first for the passage of a gaseous medium, means for transferring heat from the 70 hot medium to the gas comprising a plurality of evacuated containers carrying liquid to be vaporized in their lower portions, the lower portions of the containers extending 75 into the first mentioned duct, the upper portions carrying the vapor of the liquid extending into the other duct, and means for transferring a portion of the heat to a liquid medium consisting of a third duct in contact with the containers. 80

6. A heat exchanger comprising in combination a duct for the passage of a hot fluid medium, a second duct adjacent and parallel to the first for the passage of a gaseous medium, means for transferring heat from the 85 hot medium to the gas comprising a plurality of evacuated containers carrying liquid to be vaporized in their lower portions, the lower portions of the containers extending 90 into the first mentioned duct, the upper portions carrying the vapor of the liquid extending into the other duct, and means for transferring a portion of the heat to a liquid medium consisting of a third duct in contact with the containers and exposed to the heat 95 of the vapor therein. 100

7. A heat exchanger comprising in combination a duct for the passage of a hot fluid medium, a second duct parallel and adjacent to the first for the passage of a gaseous medium, means for transferring heat from the 100 hot medium to the gas comprising a plurality of inclined evacuated containers carrying liquid to be vaporized in their lower portions, the lower portions of the containers 105 extending into the first mentioned duct, the upper portions carrying the vapor of the liquid extending into the other duct, and means for transferring a portion of the heat to a liquid medium comprising a third duct in contact 110 with the containers. 110

8. A heat exchanger comprising in combination a duct for the passage of a hot fluid medium, a second duct parallel and adjacent to the first for the passage of a gaseous medium, means for transferring heat from the 115 hot medium to the gas comprising a plurality of inclined evacuated containers carrying liquid to be vaporized in their lower portions, the lower portions of the containers 120 extending into the first mentioned duct, the upper portions carrying the vapor of the liquid extending into the other duct, and means for transferring a portion of the heat to a liquid medium comprising a third duct 125 in contact with and exposed to the heat of the vapor in the containers. 130

9. A heat exchanger comprising in combination a duct for the passage of a hot gaseous medium, a second duct adjacent to the first

for the passage of the gaseous medium to be heated, means for effecting an exchange of heat comprising a plurality of evacuated containers partially filled with liquid to be vaporized having portions extending into the path of the gases in each duct and means for transferring a portion of the heat to a liquid

comprising a third duct through which liquid flows in heat exchange relationship with the portions of said containers in which vapor **10** is present.

In witness whereof, I have hereunto signed my name.

CHARLES B. GRADY.
